UNITED STATES PATENT OFFICE.

WILLIAM P. BETTENDORF, OF DAVENPORT, IOWA.

TIRE-ROLLING MACHINE.

SPECIFICATION forming part of Letters Patent No. 436,207, dated September 9, 1890.

Application filed May 20, 1890. Serial No. 352,685. (No model.)

To all whom it may concern:

Be it known that I, WILLIAM P. BETTENDORF, of Davenport, in the county of Scott and State of Iowa, have invented certain Improvements in Tire-Rolling Machines, of which the following is a specification.

This invention relates to that class of machines in which the tire is passed between bending-rolls, the relations of which may be changed according to the required curvature of the tire.

The improvements have reference to the means for sustaining, adjusting, and driving the rolls.

15 In the accompanying drawings, Figure 1 is a front elevation of my machine; Fig. 2, a side elevation of the same; Fig. 3, an elevation of the roll-driving gear; Fig. 4, a plan view of one of the roll-sustaining yokes. Fig. 20 5 is a side elevation of the same.

Referring to the drawings, A represents a base-frame, to which there is firmly bolted a top frame B, suitably constructed and provided with boxes to sustain the horizontal 25 main shaft C and horizontal driving-shaft D. The driving-shaft is provided with a driving-pulley d, fly-wheel d', and a pinion d², which engages a gear-wheel e on the main shaft. At its forward end, which is sustained in an 30 overhanging arm of the frame, the main shaft carries a roll E, lying immediately over a second roll F, carried by a shaft f. This shaft f is mounted in a sustaining-yoke or frame G, (separately shown in Figs. 4 and 5,) provided 35 with sustaining-trunnions g, seated in bearings in the main frame, so that the roll F may move to and from the roll E to permit the passage of tires of different thicknesses between them. In order to hold the under roll 40 up to its place, the sustaining-yoke is provided with a depending arm g¹, perforated for the passage of a rod g', which is pivoted to the frame at g², and provided at the outer threaded end with a hand-nut g³, which acts 45 through an intermediate spring g⁴ on the yoke-arm. By adjusting the nut the spring may be caused to urge the roll upward with any required degree of pressure. The spring permits the roll to give way, and thus prevents 50 breakage of the parts in the event of a very thick bar being introduced between the rolls.

The roll-sustaining yoke G also sustains a second horizontal roll I in advance of the main rolls to act on the under side of the tire. The yoke also sustains two vertical guide-rolls h² h³, to act on the edges of the tire and direct the same between the bending-rolls, that it may not be twisted out of shape. These rolls are mounted on studs fixed by nuts in a slot in the yoke, so that they may be adjusted laterally.

In rear of the main rolls there is a fourth horizontal bending-roll K, sustained in a yoke-frame L, which is constructed, mounted, and adjusted in essentially the same manner as the front yoke already described. The trunnions of this rear yoke (shown at l) are sustained in the main frame and its depending arm l' acted upon by a hand-nut l², mounted in the threaded end of the rod l⁴ fixed to the frame.

The shaft of the lower roll F is driven from the shaft C of the upper roll by the peculiarly-arranged gearing shown in detail in Fig. 3. The shaft C is provided with a pinion n, engaging a pinion n', which in turn communicates motion through a pinion n² to a pinion n³ on the shaft f of the lower roll. The pinion n' has its journals sustained in the yoke-frame n⁴, mounted to turn around the shaft C as a center. 80 The pinion n² has its journals mounted in a yoke or frame n⁵, mounted to turn on the lower roll-shaft as a center. The journals of the pinions n' and n² are connected by links n⁶. The foregoing arrangement forms in effect a 85 flexible or adjustable gear-train, which permits the lower roll and its driving-pinion n³ to rise and fall without in any manner affecting the operation of the gear or changing the depth at which the teeth engage. By 90 means of this gear frame I am enabled to drive the upper and the lower feed-rolls positively and at equal surface speeds without reference to the varying distances between them.

In operating the machine the rolls are driven in the directions indicated by the arrows, and the bar to be bent passed between the vertical guide-rolls h², over the bending-roll I, between the upper bending and feeding roll E and the feed-roll F, and finally over the bending-roll K. The rolls E and F co-

operate to feed the metal forward, while the rolls E, I, and K co-operate to effect the bending of the same. As the metal is drawn forward between the vertical rolls, they cause it 5 to pass through in a straight line, so that a lateral twist or bend becomes impossible.

Having thus described my invention, what I claim is—

1. In a tire-bending machine, the combination of three bending-rolls, a spring-supported feed-roll arranged in opposition to one of the bending-rolls and driving-gear connected to the feed-roll and to the adjacent bending-roll.
2. In a tire-bending machine, the combination of an upper power-driven bending-roll, 15 two bending-rolls arranged to act on the under side of the tire, pivoted supports for the last-named rolls, and a spring acting on one of the supports to maintain the roll in operative position, and an adjusting device acting on the other support.
3. In a tire-bending machine, the combination of a bending-roll to act on top of the tire, two bending-rolls arranged at opposite sides 25 of the top roll to act on the under side of the tire, movable supports for said under rolls, a spring acting on one of said supports to hold its roll to its operative position, an adjusting-screw connected with the other support, and 30 a yielding feed-roll arranged between the lower bending-rolls.
4. In a tire-bending machine, the upper bending-roll mounted in fixed bearing, the opposing feed-roll mounted in a movable bearing, the four pinions connecting the two roll-shafts, and the connected pivoted yokes 35 whereby the intermediate pinions are maintained and kept in proper operative positions

5. In a tire-bending machine, the combination of an upper bending-roll and a pivoted 40 spring-supported bearing provided with a feed-roll and also with a bending-roll, whereby the tire acts by depressing the feed-roll to adjust the bending-roll.

6. In a tire-bending machine, and in combination with two bending-rolls, a third bending-roll, a pivoted support therefor, and a hand-screw for adjusting said support, whereby the relation of its roll to the other bending-rolls may be varied at will. 45

7. In a tire-bending machine, and in combination with a pivoted roll-supporting yoke, the vertical guide-rolls mounted thereon. 50

8. In a tire-bending machine, the combination of a bending-roll to act on one side of the 55 tire, a pivoted feed-roll to act on the opposite side of the tire, a second bending-roll, and a pivoted bar or support, in which the feed-roll and the second bending-roll are both mounted.

9. In a tire-bending machine, the combination of a fixed horizontal bending-roll, a co-operating bending-roll F, movable with relation thereto, a support for said roll mounted on a horizontal axis located in rear of the roll, and vertical guide-rolls sustained by the roll-support in rear of its horizontal axis, substantially as described. 60

In testimony whereof I hereunto set my hand, this 8th day of May, 1890, in the presence of two attesting witnesses.

WILLIAM P. BETTENDORF.
